UNITED STATES PATENT OFFICE.

CHARLES H. WOODS, OF DECATUR, ILLINOIS, ASSIGNOR OF ONE-HALF TO ALBERT RUEBSAMEN, OF DECATUR, ILLINOIS.

COIN SORTER AND REGISTER.

1,177,671.

Specification of Letters Patent.

Patented Apr. 4, 1916.

Application filed July 16, 1915. Serial No. 40,281.

To all whom it may concern:

Be it known that I, CHARLES H. Woods, a citizen of the United States, residing at Decatur, in the county of Macon and State of Illinois, have invented a new and useful Coin Sorter and Register, of which the following is a specification.

The present invention appertains to coin sorters and registers, and aims to provide an apparatus of that character adapted especially for use in connection with a street car fare box or receptacle, for separating the nickels and dimes and registering the number of coins of each denomination, although the apparatus is adapted for other uses as well and may be constructed for sorting various sizes and number of coins or disks.

The salient features of the invention is the provision of novel means for conducting the different coins to different points where they are ejected, in connection with unique means for ejecting the coins so that they will drop into the respective receptacles provided for receiving the various sorts of coins.

It is also an object of the invention to combine with the sorting mechanism, registers which are arranged to be operated when the respective coins are ejected, so that the registers will indicate the number of coins of each class which have been deposited in their receptacles.

It is also within the scope of the invention, to provide a coin sorter and register having the features above noted, and embodying a novel assemblage and co-operation of the component parts, whereby the utility and efficiency of the appliance are enhanced.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawings, wherein:

Figure 1 is a side elevation of the apparatus. Fig. 2 is a vertical section of the

coin chute, taken on the line 2—2 of Fig. 1. Fig. 3 is a vertical section of the apparatus. Fig. 4 is a horizontal section taken on the line 4—4 of Fig. 3. Fig. 5 is a horizontal section taken approximately on the line 5—5 of Fig. 3. Fig. 6 is a horizontal sectional detail taken on the line 6—6 of Fig. 3.

In carrying out the invention, there is provided a suitable frame 1 having suitable brackets and bearings for the various parts which are supported within the frame, and the frame may be provided with side panels so as to close and protect the working parts. The frame 1 carries an upper fare box or receptacle 2, that is, when the appliance is employed for street car use, in order that the coins, such as five and ten cent pieces, in the present instance, may be deposited in the box 2 by the passengers. The coins are normally held within the box 2 by a lower shutter 3 which may be manually operated by the conductor for dropping the coins, after they have been examined through the transparent walls of the box 2, which enables the conductor, as usual, to detect the presence of spurious or counterfeit coins. When the apparatus is employed in a bank, or the like, for separating the coins, the box or receptacle 2 may naturally be eliminated, and the use of the coin box or receptacle 2 is therefore dependent upon the use to which the apparatus is put.

The frame 1 contains various parts of the sorting and registering mechanisms, and carries an upper hopper 4 below the fare box 2 which is adapted to receive the coins, this hopper 4 having a depending spout 5 which delivers the mixed coins to the coin delivering device 6, which serves to deliver the coins one at a time into the sorting or separating mechanism. The delivering device 6 embodies a circular cup 7, and an oscillatory delivering disk 8 mounted within the cup 7 upon the bottom thereof, the disk 8 being provided at one side of its center with a coin opening 9 adapted to be brought under the spout 5 for receiving the lowermost coin from the spout 5 to carry said coin from under the spout 5. The disk 8 is secured upon the upper end of an upright rock shaft 10 journaled through the bottom of the cup 7, this shaft 10 being operated in a manner which will appear hereinafter. The bottom of the cup 7 has an opening 11 at one side of the spout 5

through which the coin carried by the disk 8 drops when the disk 8 is swung to move the opening 9 from under the spout 5 and over the opening 11.

5 Supported immediately below the opening 11 of the delivering device 6 is a coin hopper 12 carried by the upper end of an upright or vertical coin chute 13. This coin chute 13 has a relatively wide channel 14 extending downwardly from the hopper 12 to a point between the ends of the chute, and has a relatively narrow channel 15 extending downwardly from the channel 14. A coin seat 16 is provided between the channels 14 and 15, or at the lower end of the channel 14, for stopping and supporting the nickels or five cent pieces, and a seat 17 is provided at the lower end of the channel 15 for stopping and supporting the 10 dimes or ten cent pieces. At this point, it might be mentioned, that the coin chute and corresponding parts may be constructed of various sizes or proportions for sorting various denominations and numbers of coins, 15 according to the dictates of necessity or convenience. The coin chute 13 is provided at one side with an outlet opening 18 for the nickels, this opening 18 being arranged adjacent the seat 16 and extending from the 20 lower end of the passage 14, and the said side of the chute 13 is provided with a second outlet opening 19 for the dimes, this opening 19 being arranged adjacent the seat 17 and extending from the lower end of 25 the passage 15.

The coin ejector comprises an upright slide or cross head 20 slidable upon outstanding guide rods 21 carried by that side of the coin chute 13 opposite the openings 30 18 and 19, coiled wire expansion springs 22 being disposed between the coin chute and bar 20 for yieldably moving the bar 20 away from the coin chute. Plungers 23 and 24 are secured to the bar 20 and project 35 slidably through that side of the coin chute 13 opposite the openings 18 and 19, and the plungers 23 and 24 are coaxial with the respective openings 18 and 19. When the bar 20 is moved away from the coin chute under 40 the influence of the springs 22, the plungers 23 and 24 are retracted out of the passages 14 and 15, respectively, but when the bar 20 is moved toward the coin chute, the plungers will be projected through the passages 45 of the coin chute and through the outlet openings 18 and 19, respectively.

Coöperating with the coin ejecting means, are coin holding means, which prevent the accidental discharge of the coins, and which 50 facilitate the proper ejection or discharge of the coins. The two coin holding means embody upper and lower plungers 25 and 26, respectively, which are mounted slidably within the upper and lower openings 18 and 55 19. The opening 18 and plunger 25 are just

slightly greater in diameter than a nickel, while the opening 19 and plunger 26 are just slightly greater in diameter than a dime, for obvious reasons. Guides 27 are carried by the coin chute 13 and the plungers 25 and 26 are slidably carried thereby, and coiled wire expansion springs 28 and 29 are disposed between the respective plungers 25 and 26 and the corresponding guides 27, whereby the springs yieldably move the plungers 25 and 26 toward and adjacent the passages 14 and 15 of the coin chute. The plungers 25 and 26 are provided with the respective flanges 25' and 26' to bear against the coin chute 13 for limiting the movement of the plungers properly so that they will not project into the passages 14 and 15. The plungers 25 and 26 have the respective bores or sockets 30 and 31 for receiving the plungers 23 and 24, respectively, when the coin ejectors operate idly. The plungers 25 and 26 also have the outstanding pins or stems 32 and 33 at those ends remote from the coin chute, and the stems 32 and 33 have the respective heads or knobs 34 and 35 at their free ends.

Means are employed for holding the plungers 25 and 26 against the tension of their springs, and to this end upper and lower pairs of leaf springs 36 and 37 are carried by the frame. The springs 36 and 37 project toward the respective plungers 25 and 26, and have the inturned hooks 38 at their free ends for receiving and holding the knobs 34 and 35 when the plungers 25 and 26 are pushed outwardly. The leaf springs or spring catches 36 and 37 are released in a manner which will be described hereinafter.

The actuating mechanism or the coin delivering device 6, the coin ejecting means or device, and the device for releasing the catches 36 and 37, embodies an upright shaft 39 journaled to the frame 1 and operated by a hand crank 40 upon the outside of the frame 1 and connected to the shaft 39 by means of the intermeshing bevel gears 41 carried by the shaft 39 and crank 40. A rotatable gear 42, having a vertical axis parallel with the vertical axis of the shaft 10 and disposed in a horizontal plane below the horizontal plane of the disk 8, intermeshes with a gear wheel 43 carried by the shaft 39, and has an upstanding wrist pin 44. A pitman 45 is pivoted at one end to the wrist pin 44 and is slidable through a pivoted element 46 carried by a radially projecting arm 47 secured to the rock shaft 10 of the delivering device 6. A stop 48 is secured upon the pitman 45 and is arranged to bear against the element 46 when the gear wheel 42 is rotated to move the wrist pin 44 toward the arm 47, so that the said arm 47 will be forcibly swung in one direction. A coiled wire expansion spring 49 is

disposed between the element 46 and a head or collar 50 carried by the free end of the pitman 45, whereby the spring 49 will yieldably swing the arm 47 in the other direction.

5 The coin ejecting device and shaft 39 are operatively connected; and to this end, a cam 51 is carried by the shaft 39 and bears against a roller 52 carried by the bar 20 of the ejecting device, the cam 51 being so proportioned as to properly project the plungers 23 and 24.

10 The means for releasing the catches 36 and 37 embodies an upright rock shaft 53, journaled to the frame between the catches of the upper and lower pairs, and an angle iron tappet or cam 54 has its elbow secured to the shaft 53, whereby the flanges of the tappet or cam 54 will swing the catches 36 20 and 37 apart when the shaft 53 is oscillated properly. The lower end of the shaft 53 is operatively connected with the shaft 39, and to this end, the lower end of the rock shaft 53 has an angularly or radially projecting 25 arm 55 to which one end of a plunger rod 56 is pivoted. The other or free end of the rod 56 coöperates with a suitable cam 57 carried by the driving shaft 39, whereby the rod 56 will be timely thrust away from the 30 shaft 39 by the cam 57 for separating the catches 36 and 37 properly.

35 The lower portion of the frame 1 carries a slideable drawer 58 having the receptacles 59 and 60 for receiving the dimes and nickels, respectively. The receptacle 59 is disposed below the dime ejecting means so as to catch the dimes, while the receptacle 60 is located at one side of the ejecting means. The nickels are delivered from the 40 nickel ejecting means into the receptacle 60 by means of an inclined chute or run way 60' extending downwardly from the nickel ejecting means into the receptacle 60.

45 Registers or counters 61 and 62 are carried by the frame to be operated by the nickel and dime ejecting means, respectively. A lever 63 carried by the frame is operatively connected to the register 61 and has its free end arranged in the path of the 50 plunger 25 whereby when said plunger is moved outwardly, it will swing the lever 63 for advancing the register 61 one step. Similarly, a lever 64 carried by the frame is operatively connected to the register 62 and 55 has its free end arranged in the path of the lower plunger 26, whereby when said plunger is moved outwardly, it will swing the lever 64 for advancing the register 62 one step.

60 In operation, the mixed dimes and nickels are dropped into the hopper 4 and will be conducted downwardly into the spout 5, the coins seating flatly one upon the other within the spout 5 to provide a pile of coins adapted to be carried one at a time by the

delivering device 6 to the sorting device. The operator turns the crank 40, so as to rotate the driving shaft 39, and the gear wheel 42 will naturally be rotated so as to reciprocate the pitman 45. When the pit- 70

man 45 moves toward the arm 47, the stop 48 will strike the element 46 carried by the arm 47, and this will forcibly swing the rock shaft 10, so that the disk 8 carried by the rock shaft will be rotated properly to 75

bring the coin opening 9 thereof under the spout 5. The opening 9 will thus receive the lowermost coin, whether it be dime or nickel, and then when the pitman 45 is moved away from the arm 47, the spring 80 49 will yieldably swing the arm 47 in the opposite direction. This will rotate the disk 8 in the opposite direction so as to move the opening 9 from under the spout 5 and over the outlet opening 11, and as a 85

result, the coin will drop from the opening 9 through the opening 11 into the hopper 12. The coins are thus delivered one at a time from the spout 5 to the coin chute 13.

The hopper 12 is of such formation that the 90 coins will be turned from any angle to an upright position when entering the passage 14. If the coin is a nickel, it will be stopped by the seat or stop 16, and will therefore register with the opening 18, but if the 95 coin is a dime, it will pass on down into the passage 15 so as to rest upon the seat or stop 17 in registration with the opening 19.

100 In this manner, the various denominations or sizes of coins are stopped at various points, in order that the coins may be properly ejected according to their value. Now, assuming that a nickel N is within the passage 14 upon the seat 16, the cam 51 being rotated with the shaft 39 and bearing against the roller 52 carried by the bar or yoke 20 will push the bar 20 toward the coin chute, so that the plungers 23 and 24 will be projected through the coin passages. The upper plunger 23 will impinge against 110 the nickel N and will push the nickel through the outlet opening 18, the plunger 25 being forced outwardly with the nickel.

The lower plunger 24 in the absence of a dime within the passage 15, will simply move idly within the bore 31 of the plunger 26 without moving said plunger. When the plunger 25 is moved outwardly, as aforesaid, the knob 34 thereof will be moved be- 115

tween the spring catches 36 and will snap in back of the hooks 38 of the catches 36, so that the plunger 25 is held against the tension of its spring 28. Then, when the cam 51 completes its revolution to allow the yoke or bar 20 to move back to initial 120 or normal position under the influence of the springs 22, the plunger 25 is held at the position indicated, while the plunger 23 leaves the plunger 25, and the nickel which was previously clamped between the plun- 125

130

gers 23 and 24 will be released, and will fall downwardly from between the upper guide 27 and coin chute 13 down the chute 60' into the receptacle 60. When the plunger 25 is moved outwardly, it will swing the lever 63 for operating the register 61, while the lower plunger 26 which remained idle, will render the dime register 62 passive during the time that the nickel is being ejected. 10 When a dime D is in the chute 13 upon the seat 17, it will be moved outwardly through the opening 19 by the plunger 24, and will move the plunger 26 therewith, while the plunger 23 will simply move idly within the bore 30 of the upper plunger 25. The dime is thus carried out of the coin chute, similar in the manner in which the nickel was, and the plunger 26 will be held by the catches 37 similar to the manner in which 15 the plunger 25 is held by the catches 36. The dime may thus be released when the bar 20 moves backward to initial position, and will drop into the receptacle 59. The cam 57 is so arranged as to operate the 20 plunger rod 56 at the proper time after the coin has been released, to rotate the rock shaft 53 for separating the catches, in order that the respective plunger 25 or 26 will be released, and will therefore return 25 to initial position under the influence of its spring. The plungers 25 and 26 are thus released after the coins are ejected, to return to normal positions for new operations. The lever 64 is operated by the plunger 26 30 for actuating the register 62, it being noted that both registers are only operated when the respective coins are being ejected.

The operation of the apparatus is continued until all of the coins are taken from the spout 5 and sorted, the operation being continuous.

The sorted coins may be taken from the drawer 58 after the drawer is slid open, and if desired, the drawer may normally be held 45 shut by a suitable lock, to prevent access thereto. The amount of coins contained in the drawer will be indicated by the registers 61 and 62, which is desirable for reasons which will be obvious.

50 The apparatus illustrated and described is adapted particularly for street car use, wherein it is only necessary, ordinarily, to separate dimes and nickels, change being made, as necessary, by the conductor to supply the passengers with dimes and nickels. It is evident, however, that by increasing the number of coin passages of the coin chute, and correspondingly increasing the number of ejecting means, a larger number 55 of coins of various denominations may be sorted or separated.

Having thus described the invention, what is claimed as new is:—

1. In a coin sorter, a coin chute having 60 means at different points of its length for

stopping coins of various denominations and having outlet openings adjacent said means, yieldable members normally disposed in said openings, ejecting means having plungers slideable through the chute for 70 ejecting the coins through said openings and pushing said members with the coins, pairs of catches, said members having knobs engageable between and adapted to be held by the catches when the members are moved 75 outwardly, a cam between the catches of the respective pairs for separating them, and means for operating the ejecting means and cam whereby the catches are released during 80 the retraction of the plungers. 80

2. In a coin sorter, a coin chute having means at various points of its length for stopping coins of different denominations, and having outlet openings at one side adjacent said means, ejecting means including 85 plungers slideable through the opposite side of the chute to project through the chute and said openings for ejecting the coins through said openings, spring pressed plungers normally disposed in said openings and 90 adapted to be moved outwardly with the coins, said spring pressed plungers having bores for receiving the ejecting plungers, and means for momentarily holding the 95 spring pressed plungers when they are moved outwardly and until the ejecting plungers are retracted.

3. In a coin sorter, a coin chute having means at various points of its length for stopping coins of different denominations, and having outlet openings at one side adjacent said means, ejecting means including 100 plungers slideable through the opposite side of the chute to project through the chute and said openings for ejecting the coins 105 through said openings, spring pressed plungers normally disposed in said openings and adapted to be moved outwardly with the coins, said spring pressed plungers having bores for receiving the ejecting plungers, 110 catches engageable with the spring pressed plungers when they are moved outwardly to hold the same, and means for releasing 115 said catches when the ejecting plungers are retracted. 115

4. A coin sorter comprising a coin chute having means at various points of its length for stopping coins of different denominations and having coin outlet openings at one side adjacent said means, ejecting means including plungers slideable through the other side of the chute so as to be projectable through the chute and said openings, plungers normally disposed in said openings and having bores for receiving the ejecting plungers, guides for 120 slidably supporting the second mentioned plungers, expansion springs between said guides and second mentioned plungers to 125 yieldably move the second mentioned plungers to 130

gers in said openings, the second mentioned plungers having stems provided with knobs, pairs of spring catches for receiving and holding said knobs when the second mentioned plungers are moved outwardly, a cam disposed between the catches of the respective pairs, and means for operating the ejecting means and cam whereby the catches are released during the retraction of the ejecting plungers.

5. In a coin sorter, a coin chute having means for stopping a coin of one denomination and having an outlet opening adjacent said means, ejecting means including a plunger projectable through the chute and said opening to eject the coin, means for

delivering coins one at a time into the chute, a spring pressed member normally disposed in said opening and adapted to be moved outward with the coin when it is ejected, 20 means for holding said member when it is moved outward, and means for releasing said holding means during the retraction of the plunger.

In testimony that I claim the foregoing 25 as my own, I have hereto affixed my signature in the presence of two witnesses.

CHARLES H. WOODS.
